UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A HANDLE FOR BRUSHES, &c.

SPECIFICATION forming part of Design No. 18,974, dated March 26, 1889.

Application filed February 16, 1889. Serial No. 300,169. Term of patent 7 years.

To all whom it may concern:

Be it known that I, HENRY BERRY, a citizen of the United States, residing at Shelton, in the county of Fairfield and State of Connecticut, have invented and produced a certain new and original Design for a Handle for Brushes and Similar Articles, of which the following is a specification, reference being had to the accompanying drawing, which forms a part thereof, and which shows a plan view of a handle shaped in conformity with my design.

The leading feature of my design consists in the shape or outline of the handle and also in the details of ornamentation which appear thereon. Near its top end the handle is enlarged, as at *a*, and from the enlarged portion it tapers downward in a gentle curve toward the point *b*, which is turned upwardly and is convolved at its extremity. Upon the enlarged portion of the handle appears the representation of a flower, *c*, and about the central flower the representations of smaller flowers, *d*, and a spray of leaves, *e*. From beneath the figures last referred to a series of flutings,

f, appear upon the handle and follow the outline of the same downward to the extremity thereof, each of the fluted figures gradually diminishing in size as the handle diminishes in size.

I claim—

The design for handles for brushes and similar articles herein shown and described, the same being formed with an enlarged and rounded upper portion, and curving and tapering thence to its lower extremity, which is turned upwardly and convolved, and having the representation of flowers upon the enlarged portion, and of the fluted figures extending from said enlarged portion downward toward the point and following the outline of the handle, as specified.

In testimony whereof I affix my signature in presence of two witnesses.

HENRY BERRY.
